UNITED STATES PATENT OFFICE.

HERMAN LAQUA, OF ZUMBRO FALLS, MINNESOTA.

GRAIN-BINDER ATTACHMENT.

1,301,717.

Specification of Letters Patent. Patented Apr. 22, 1919.

Application filed February 17, 1919. Serial No. 277,567.

To all whom it may concern:

Be it known that I, HERMAN LAQUA, a citizen of the United States, residing at Zumbro Falls, in the county of Wabasha and 5 State of Minnesota, have invented certain new and useful Improvements in Grain-Binder Attachments, of which the following is a specification.

The present invention comprehends generally improvements in that class of inventions known as harvesters and more particularly relates to a grain binder attachment.

It is the primary aim and object of this 10 invention to provide a device of the above mentioned character designed to be attached to a grain binder for holding the grain in position with respect to the knotting and binding mechanism.

More particularly the present invention 15 contemplates the provision of a device of the above mentioned character wherein there is employed a pair of pivotally and resiliently mounted grain holding arms preferably associated with the spring rail of a 20 binder and positioned on opposite sides of the binding and knotting mechanism so as to temporarily hold the grain back in proper relation to the said mechanism until the completed bundles are ready to be discharged 25 from the machine.

Among the other aims and objects of this 30 invention may be recited the provision of a device of the above mentioned character with a view to compactness and wherein the 35 number of parts are few, the construction simple, the cost of production low and the efficiency high.

Other objects, as well as the nature, characteristic features and scope of this invention 40 will be more readily apparent from the following description taken in connection with the accompanying drawings, and pointed out in the claims, forming a part of this specification.

45 The invention is clearly illustrated in the accompanying drawings, in which:

Figure 1 is a perspective view showing the 50 grain holding devices attached to the spring rail and positioned on opposite sides of the binding and knotting mechanism of the binder,

Fig. 2 is an enlarged side elevational detail of one of the grain holding devices, and

55 Fig. 3 is a front elevational detail of the same.

Similar characters of reference are em-

ployed in all of the above described views, to indicate corresponding parts.

Referring now, more particularly, to the accompanying drawings there is illustrated 60 a portion of a self-binder and includes the usual spring rail A suitably supported over the deck B of the binder while operatively associated with the spring rail and positioned on opposite sides of the binding and knotting mechanism C are the improved grain holders indicated generally by the letter D designed for temporarily holding the grain back in proper relation to the binding and knotting mechanism until the completed 65 bundles are ready to be discharged from the machine.

In the present instance each grain holding device may be said to consist of an attaching arm 1 having an attaching portion 2 secured to the spring rail as by suitable fasteners 3 provided at its inner terminal with a depending flange 4 which in addition to bracing the attaching portion 2 acts to accomplish another purpose as will hereinafter 70 appear. The main portion of the attaching bracket preferably is extended upwardly at its inclination and of course rearwardly from the spring rail. Swingably connected to the outer end of the bracket 1 is one of 75 the sectional holding arms generally designated by the numeral 5. In reducing this feature of the invention to practice, the inner section may be said to consist of spaced bars 6 mounted upon opposite sides and at 80 the inner end of the outer section in the form of an elongated bar 7 preferably by means of a nut and bolt arrangement 8. A similar fastening means 9 serves to pivotally connect the bars 6 on opposite sides of the outer 85 portion of the attaching bracket 1. The nut and bolt arrangement 9 serves merely as pivotal means for the arm 5 but the nut and bolt arrangement 8 acts also as a means for clamping the outer section or deck engaging bar 7 between the inner section or the relatively short spaced bar 6 and in various 90 positions of angular adjustment.

In order to yieldingly hold the deck engaging bar 7 in engagement with the deck B of 105 the binder, resilient means such as a coiled contractile spring 10 is employed, the outer end being connected to an eye-bolt 11 carried by the bar 7 while the inner end terminates in a ring or loop 12 which is engaged with 110 the depending flange 4 of the attaching bracket.

In use, it is apparent from the brief description that the pivotally mounted grain holding or retarding arm 5 being held in yielding engagement with the deck B of the binder by the springs 10 will act to temporarily hold or retard the grain in proper relation to the binding and knotting mechanism C until the completed bundles are ready to be discharged from the machine, the weight of the bundles of course overcoming the tension of the spring 10 so that the arm 5 will raise upwardly allowing the bundles to pass down the deck or platform B as is apparent. At times it is desirable to arrange the arm 5 in an inactive position and in such event it is only necessary to swing the same upwardly beyond the center whereupon the springs 10 will become inactive and the arms will rest on the windshield E of the binder as is apparent.

It is believed in view of the foregoing description that a further detailed description of the operation of the invention is entirely unnecessary, likewise, it is believed that the advantages of the invention will be readily apparent.

Still further embodiments of the invention than those herein especially defined may be resorted to as conditions or preference may dictate, as may be in keeping with the hereto appended claims.

Having thus fully described the invention what is claimed as new and desired to be secured by Letters Patent, is:—

35 1. A grain holding attachment for self-

binders including a spring rail engaging and supporting bracket, a sectional arm composed of an inner section and an outer section, means for pivotally connecting the inner end of the inner section to the bracket, means for clamping the outer sections in various positions of angular adjustment with respect to the inner section, and resilient means between the outer section of the arm and the bracket for yieldingly holding the outer section of the arm against the deck of the binder.

2. A grain holding attachment for binders including a spring rail engaging bracket having an attaching portion and a supporting portion and also formed at its attaching portion with a depending flange, a sectional grain holding arm including an inner section consisting of spaced bars and an outer section in the form of an elongated bar, means for releasably clamping the inner end of the bar between the outer portions of the inner spaced bars so that the outer bar will lie in various positions of angular adjustment relative to the inner bars, means for pivotally connecting the inner bars to the supporting portions of the bracket and a coiled contractile spring having its respective ends connected to the outer bar and to the flange on the bracket for yieldingly holding the outer end of the outer bar in engagement with the deck of the binder.

In testimony whereof I affix my signature hereto.

HERMAN LAQUA.
